FLUID FUEL BURNER

Philip A. Celander, Bloomington, Ill., assignor to
Williams Oil-O-Matic Heating Corporation,
Bloomington, Ill., a corporation of Illinois

Application June 28, 1934, Serial No. 732,767

2 Claims. (Cl. 236—15)

This invention relates to improvements in fluid fuel burners for cooking ranges and more particularly to a control for regulating the heat produced by the burner in accordance with the temperature required within the range.

With these and other objects in view, reference is made to the accompanying sheets of drawings which illustrate preferred forms of this invention.

Figure 1 is a view in perspective illustrating an application of this invention to a cooking range, with parts broken away and parts indicated in section.

Figure 2 is an enlarged detail view, partly in front elevation, with parts broken away and contracted, and parts in vertical section.

Figure 3 is a view similar to Figure 2 illustrating a modified form of this invention.

Figure 4 is a view similar to Figure 3, illustrating another form of this invention.

Figure 5 is a fragmentary view, partly in end elevation, of Figure 2, and partly in section.

Figure 6 is a diagrammatical wiring diagram illustrating a modification of this invention to operate automatically.

Figure 1 illustrates a cooking range 1 such as employed in hotels, restaurants, hospitals, schools, and the like, including a cooking top composed of flat plates 2 and ovens 3. A commercial fluid fuel burner 4 is shown mounted upon the left hand end of the range 1 preferably of the type illustrated in the patent to Walter W. Williams, No. 1,976,317, dated October 9, 1934, which includes a motor 5 operating a fluid fuel pump 6 and a fan blower for directing a stream of air through a draft pipe 7 into the interior or combustion chamber 8 of the range.

The particular type of fluid fuel burner disclosed in said Williams patent is provided with means for regulating the supply of fluid fuel and for limiting the supply of air projected through the draft pipe 7, which may be operated in unison to regulate the amount of heat produced or the size of the flame. This said patent discloses a manual control for these parts and this invention contemplates an automatic control to maintain an even temperature below the top plates and in the ovens.

As shown in the fragmentary view in Figure 5, the fuel pump 6 is provided with a cam 9 mounted on the rotatable shaft 10 which is adapted to control the flow of fuel from the pump, and the draft pipe 7 is provided with a butterfly valve or draft regulator 11 mounted upon the rotatable shaft 12 adapted to control the flow of air therethrough. The face of the pump 6 is provided with a casing 13 into which the fluid fuel regulating shaft 10 passes from the pump. The casing 13 mounts below the shaft 10 and in parallel relation thereto an actuating shaft 14 which is

connected through the crank 15 and links 16 with the operating shaft 12 of the draft regulator 11 in the draft pipe 7. The end of the shaft 10 within the casing 13 is provided with a depending arm 17 connected thereto, and the end of the shaft 14 within the casing 13 is provided with a depending arm 18 extending upwardly therefrom and overlapping the arm 17. The arm 18 is provided with a slot 19 and the arm 17 is provided with a stud 20 adapted to be engaged within and travel over said slot 19. The depending portion of the arm 18 diametrically opposite the slot 19 is provided with a gear 21 concentric to the center of the shaft 14. Mounted within the casing below the arms 17 and 18 is a segment 22 mounted on a pivot 23 in alignment with the centers of the shafts 10 and 14 and having a segment gear 24 meshing with the teeth of the gear 21. The parts are so proportioned that a rotation of the segment 22 in one direction imparts a rotation to the actuating shaft 14 to open the draft regulator 11 the maximum capacity for the draft pipe 7 and through the stud and slot connection with the arm 17 to rotate the cam 9 to increase the capacity of the fluid fuel pump to maximum. Rotation of the segment 22 in the opposite direction reverses the operation of the shafts 10 and 14 to reduce the fluid fuel and air supply to a minimum.

This invention contemplates the imparting of an automatic movement to the segment 22 actuated by the temperature within the range. In the form shown in Figures 1 and 2, an operating link 25 is shown connected to the segment 22 above the pivot thereof with its other end extending into a tube 26 arranged parallel thereto and extending from one end of the range to the other through the combustion chamber 8 and ovens 3. It is preferable to provide a bar 27 mounted within the tube connected at one end to the link 25 and secured at its other end to the end of the tube by a pin 28. The metallic bar is formed of a metal which is readily expandable and contractible in accordance with the variations of its temperature so that when the oven is cold the bar 27 will be contracted imparting a rotation to the segment 22 to actuate the shafts 10 and 14 to provide a maximum supply of fluid fuel and air to the combustion chamber. When the fluid fuel burner 4 is set in operation and the fuel ignited, the temperature within the combustion chamber and ovens will gradually increase, whereupon the bar 27 will be caused to expand to rotate the segment 22 to gradually reduce the supply of fuel and air to the combustion chamber and thereby reduce the temperature within the range and will maintain an even temperature within the range irrespective of the opening and closing of the oven doors or radiation from the top plates.

- Figure 3 illustrates a modified form of this invention in which the link 25^a is extended through a tube 26^a, which passes only through the combustion chamber 8, and the end of the link 25^a opposite the segment 22 is provided with a sliding connection 29 to engage the free end of a U-shaped bi-metallic thermal member 30 having its opposite end secured to the wall of the oven 3 opposite the tube 26^a. The thermal member 30 is so constructed that when the range is cold, the free end will be contracted, as shown in the dotted lines, to rotate the segment 22 to provide a maximum supply of fuel and air to the burner 4. As the temperature within the oven increases, the free end of the thermal member 30 will expand, causing the lever 26^a to move in the opposite direction to cut down the supply of fuel and air to the burner in the same manner as described in Figure 2.
- Figure 4 illustrates a still further modification. In this type the casing 13 is extended to form a chamber 31 preferably supported against the adjacent end of the range 1 and mounts an expandable and contractible metallic bellows 32 with the reciprocating closed end thereof adjacent the casing 13 and provided with a link 25^b having one end attached to the segment 22 and the other to the reciprocable end of the bellows. The other end of the bellows is closed and communicates with the pipe 33 preferably passing through a tube 26^b mounted within the combustion chamber 8 which tube extends therebeyond and through the adjacent oven 3 and communicates with a bulb or closed flask 33^a mounted on the wall of the oven 3 opposite the combustion chamber. This bulb or flask is filled with readily expandable and contractible gas or liquid, such as acetone, which is readily responsive to temperature changes so that when the range is cold the liquid will contract and allow the bellows 32 to contract to rotate the segment 22 to the maximum amount of fuel and fluid to the fluid fuel burner 4. When burner mechanism is started, the heat therefrom will cause the fluid within the bulb 33^a to expand, causing the bellows to expand, to impart a rotation to the segment 22 in the opposite direction in the same manner as described in connection with the controls illustrated in Figures 2 and 3.
- In the controls above described, it is necessary to manually start and stop the fuel-burning mechanism or to provide some independent means for starting the burner motor and igniting the flame. The control will operate as long as the burner mechanism is operating to vary the supply of air and fuel from the maximum to the minimum, without a shutdown, in accordance with the demands of the range.
- This invention also contemplates an automatic starting and stopping of the fuel-burning mechanism, as shown in the wiring diagram illustrated in Figure 6. In this type, a switch, preferably a mercury tube switch, 34 is mounted upon the segment 22, which is connected in series with the motor M of the fluid fuel-burning mechanism, so that when the link 25 has been extended to the limit of its movement, after reducing the supply of fuel and air to a minimum, will cause the switch 34 to open the motor circuit.
- A hand switch H is provided in the motor circuit and a transformer T is connected in parallel

with the motor circuit, which transformer provides an ignition circuit when the hand switch H is closed to a continuously operating spark gap S adapted to ignite the fluid fuel. To initiate the operation of the fluid fuel burner when the range is cold, it is only necessary to close the hand switch H as the retraction of the link 25 by the expandable and contractible rod 27 shown in Figure 2, or the contraction of the bi-metallic member 30 shown in Figure 3, or by the retraction of the bellows 32 shown in Figure 4, has oscillated the segment 22 to operate the parts controlled thereby to supply the maximum fuel and air, and has also closed the mercury switch 34. The closing of the hand switch H immediately energizes the ignition device S and starts the operation of the motor to supply fuel and air to the burner mechanism, which is at once ignited by the spark gap S. Thereafter, the operation of the control and fluid fuel burner will be continuous until the motor circuit is manually opened. In the event that the temperature within the range becomes greater than desired with the minimum supply of fuel and air, the mercury switch 34 will open the circuit to the motor, the fuel-burning mechanism will become idle and will remain so until the range calls for more heat, as the links 25, 25^a, or 25^b, as the case may be, are retracted and the mercury switch 34 again closed.

What I claim is:

1. In a fluid fuel burning cooking range including an oven, a combustion chamber at one end having a passage for the hot gases of combustion over said oven, a fluid fuel burning mechanism mounted upon the exterior of said combustion chamber at one end of the range, means for regulating the supply of fuel within the burner mechanism having an exteriorly projecting operating shaft, means for regulating the supply of air within the burner mechanism having an exteriorly projecting operating shaft extending in parallel relation to the first shaft, a housing attached to the burner mechanism mounting the free ends of said operating shafts, the ends of said operating shafts within the housing mounting arms to overlap each other provided with a pin and slot connection whereby rotation of one arm imparts a rotation to the other, one of said arms having a portion in the form of a gear concentric with its respective operating shaft, a segment gear meshing therewith mounted within said housing on a pivot in line with said operating shafts, an operating link connected at one end to said segment between its pivot and the adjacent operating shaft and having its other end extending within the adjacent wall of the combustion chamber, and pivotally to one end of a contractible and expandable member mounted therein and responsive to temperature changes within said oven.

2. The structure of claim 1, wherein the fuel burning mechanism is electrically operated and an electric switch connected in series with the burner motor is mounted upon said segment so that after the operating link actuated by the expansion of its attached member has reduced the supply of fuel and air to a minimum, further movement will open said switch and render said burner inoperative.

PHILIP A. CELANDER.
